UNITED STATES PATENT OFFICE.

BENJAMIN LESTER HOCH, OF NEW YORK, N. Y.

TOOTHBRAH CABINET.

Application filed May 20, 1921, Serial No. 471,098. Renewed July 18, 1924.

To all whom it may concern:

Be it known that I, BENJAMIN LESTER HOCH, a citizen of the United States, and resident of New York city, in the county of 5 Kings and State of New York, have invented certain new and useful Improvements in Toothbrush Cabinets, of which the following is a specification.

My invention relates to an improved form 10 of sanitary wall cabinet for storing and sterilizing tooth brushes. It is the present practice in most households to leave the tooth brushes of the different members of the family either exposed to the outside air 15 or to mount them on a rack in the medicine closet where they are only indifferently protected from dust and are subjected to, and not infrequently absorb, some of the disagreeable chemical odors which may happen 20 to be present in the medicine cabinet. Further it not infrequently happens that there is some confusion in the identification 25 of the tooth brushes of the different members of the family and of course any accidental use of the wrong tooth brush is very apt to have an unpleasant if not unsanitary effect.

Accordingly, one of the objects of the invention is to provide a simple tooth brush 30 containing and treating cabinet by means of which each brush can be housed in its easily identified position and by means of which each brush when so housed will be subjected to a continuous bacteriological and chemical 35 cleansing treatment so that the user is always assured that his particular brush is clean.

The invention further features a device of the class outlined which will be extremely 40 simple in structure, so as to minimize the cost of production and which will be designed to facilitate the ready cleaning of the cabinet while in position.

Still another object of the invention is to 45 provide a cabinet which features small size and from which any desired brush can be removed quickly and conveniently without any necessity of the user touching any other brush in the assemblage.

Still another object of the invention, and 50 featuring economy in the use of the material necessary to construct the device, is the desire to provide an organization of parts which will insure the storing and diffusing 55 of an antiseptic, preferably of the class of such substances which will generate a light-

er-than-air sterilizing gas, and the locating of the brush supporting rack in the cabinet and in position to bring the bristle portions of the tooth brushes in the space where these 60 light gases tend to accumulate when the front door of the cabinet is in closed position.

Various other objects and advantages of the invention will be in part obvious from 65 an inspection of the accompanying drawings and in part will be more fully set forth in the following particular description of one form of mechanism embodying my invention, and the invention also consists in 70 certain new and novel features of construction and combination of parts hereinafter set forth and claimed.

In the accompanying drawings:

Figure 1 is a perspective view showing 75 a preferred embodiment of the invention with the door in closed position;

Figure 2 is a view in front elevation of the showing in Figure 1 with the door in open position, with part of the front of the 80 casing broken away to show internal construction, and with a plurality of different sized tooth brushes shown in ghost outline and mounted in the cabinet;

Figures 3 and 5 are each horizontal sec- 85 tional views taken respectively on the lines 3-3 and 5-5 of Figure 4; and

Figure 4 is a vertical sectional view taken on the line 4-4 of Figure 2.

In the following description and in the 90 claims, parts will be identified by specific names for convenience of expression but they are intended to be as generic in their application to similar parts as the art will permit.

In the drawings there is shown a cabinet 95 having a relatively small dimension from front to rear, having a height to accommodate the tooth brushes for which the device is intended to be used, and having a 100 width largely dependent on the number of tooth brushes for which the cabinet is designed. In the illustrated showing the cabinet is formed of sheet metal as this lends itself to a simple stamping operation in the 105 formation of the parts and the providing of a device which is neat in appearance and which can be finished with white enamel or other coating to give a clean looking effect.

The cabinet illustrated includes a back 110 10, bottom 11, top 12, front portion 13 and connecting side portions 14. The front por-

tion 13 is provided with an opening which, considered vertically, is of a size to permit the ready removal of the tooth brushes therefrom, as shown more particularly in Figure 2. The back is provided with several screw holes 15 so arranged that when the cabinet is disposed in position against a flat support such as a wall, and screws disposed in the holes 15 the interior of the casing is hermetically sealed. The front opening is hermetically sealed by means of a door 16 hinged by means of conventional hinge connections 17 to one side of the front 13.

15 It will be thus seen that when the door is closed the interior of the mounted cabinet is hermetically sealed and thus encloses the antiseptic fumes, gases or other substances desired to be confined in the cabinet.

20 A series of lugs 16' project into the interior of the casing from the sides 14 and are positioned below the lower edge of the door opening to provide a support for a removable partition 17' which acts to divide 25 the interior of the cabinet into two compartments, a lower antiseptic-containing-compartment 18, containing an absorbent fabric 19 and into an upper, tooth-brush-containing-compartment 20 facing the opening. The partition 17' is provided with 30 perforations 21 so as to permit the antiseptic fumes to rise from the compartment 18 and diffuse throughout the compartment 20. The partition is provided with a handle 35 22 which facilitates the ready removal of the partition when recharging the antiseptic-containing-compartment.

40 A tooth brush supporting rack 23 projects forwardly from the back 10 into the tooth brush containing compartment 20. The rack is provided at its front edge with a plurality of horizontally spaced apart tooth brush handle containing recesses 24 which are designed to receive the reduced neck 45 portion *a* of the tooth brushes *b*. This rack is so disposed relative to the top 12 of the cabinet that the bristle portions *c* of the brushes are close to the top and in position so as to be contained within the body of the 50 antiseptic gases which collect at the upper portion of the tooth brush containing compartment. In order to maintain the presence of this light gas within the compartment, even when the door is opened, the 55 upper portion of the front extends downwardly for some material distance to form a depending flange apron 25 as shown more particularly in Figure 2. As there is no leakage through the top of the cabinet it 60 will be seen that there will, at all times, be present some of the antiseptic gases in the upper bristle containing portion of the cabinet. It is appreciated that this flange will be made as deep as possible, taking into 65 consideration the desire to have the brushes

removed easily from the compartment without unnecessarily increasing its all over depth.

In order to feature the small depth of the cabinet as a whole the rack 23 is disposed relative to the top of the antiseptic containing compartment so that there will be just sufficient room to accommodate the handle portion *d* of the longest brush in the set without any material excessive waste space 75 below the tooth brushes.

In operation it will be understood that the cabinet, properly cleaned, will have its antiseptic containing compartment charged with an antiseptic, preferably of the type 80 which will generate fumes lighter than air. The fumes will gradually form, pass upwardly through the perforations 21, traverse past all portions of the brushes and accumulate in the upper portion of the compartment in position to maintain a permanent bath of antiseptic gases about the bristle portion of the brushes. The gases will, of course, eventually penetrate to all parts 85 of the bristles and in a short time the 90 brushes will be sterile.

When the door is in closed position the gases are held within the cabinet but when it is desired to use one of the brushes the 95 door can be opened, the proper brush removed and the door quickly closed. When cleaned the used brush can be restored to its proper recess in the rack and the door carefully closed. As the charge of antiseptic becomes exhausted the partition can be 100 removed, a fresh charge of antiseptic poured onto the absorbent material 19, the partition replaced and the device is ready for continued use.

By means of a device of this character it 105 is possible to maintain each tooth brush separated from all the other tooth brushes in the set and at the same time there is insured that each brush is properly treated with the contained antiseptic. As the cabinet is dust and even air tight the contained 110 brushes are protected and in general a neat, easily constructed and pleasing bath room fixture is provided.

115 While I have shown and described, and have pointed out in the annexed claims, certain novel features of my invention, it will be understood that various omissions, substitutions and changes in the form and details of the device illustrated and in its operation may be made by those skilled in the art without departing from the spirit of the invention.

Having thus described my invention, I 125 claim:

A tooth brush cabinet comprising a sheet metal body portion provided with an opening in the front thereof, lugs projecting from opposite sides of the body portion into the interior of the cabinet adjacent the bot- 130

tom thereof, a perforated partition removably located on said lugs withdrawable bodily through the opening and coacting to form an antiseptic containing compartment in the lower portion of the cabinet, a plate extending between the side walls of the cabinet and constituting a tooth brush supporting rack secured to said body portion adjacent its upper portion, said rack provided 10 along its outer edge with a plurality of horizontally spaced apart brush handle receiving recesses, each adapted to receive the han-

dle of a tooth brush, said rack being positioned above the partition a distance to accommodate the handle portion of the brushes therebetween and thus position the brushes above the antiseptic containing compartment and a metallic door for closing said front opening.

Signed at New York city, in the county of Kings and State of New York, this 17th day of May, A. D. 1921.

BENJAMIN LESTER HOCH.
